UNITED STATES PATENT OFFICE.

GEORGE S. HILL, OF STRAFFORD, NEW HAMPSHIRE, ASSIGNEE, BY MESNE ASSIGNMENTS, TO UNITED SHOE MACHINERY CORPORATION, OF PATERSON, NEW JERSEY, A CORPORATION OF NEW JERSEY.

SAFETY DEVICE.

1,266,017.

Specification of Letters Patent.

Patented May 14, 1918.

Application filed April 22, 1916. Serial No. 92,943.

To all whom it may concern:

Be it known that I, GEORGE S. HILL, a citizen of the United States, residing at Strafford, in the county of Strafford and State of New Hampshire, have invented certain new and useful Improvements in Safety Devices; and I do hereby declare the following to be a full, clear, and exact description of the invention, such as will enable others skilled in the art to which it appertains to make and use the same.

The present invention relates to safety devices for preventing the accidental falling or too rapid lowering of a tipping portion or head of a machine.

In many types of machines the head or some portion of the machine is mounted to tip or tilt upon a stationary portion or base for the purpose of giving access to the parts beneath for inspection or adjustment, or for some other reason. Such tipping heads or portions are often heavy and inconvenient to manipulate, so that an operator is liable to suffer injury to his fingers or hands, or the machine to be damaged by the accidental falling or too rapid lowering of the tipping portion or head.

One of the objects of the present invention is to avoid such liability of injury to the operator or damage to the machine by providing means which will prevent the accidental dropping or the too rapid lowering of the head or other portion of the machine.

Another object of the present invention is to provide means whereby the tipping portion or head may be freely raised to any desired extent and automatically retained in such raised position.

With these and other objects in view, as will be apparent from the following description, the present invention consists of the devices and combinations of devices herein-after described and more particularly defined in the claims.

In the accompanying drawings which illustrate what is now considered the preferred embodiment of the present invention as applied to a buttonhole sewing machine of the type disclosed in my pending application for patent, Serial No. 104,449, filed June 19, 1916, Figure 1 is a side elevation showing the stationary base and tilting head of such a machine provided with the safety device herein-after described; Fig. 2 is an

enlarged side elevation of the safety device 55 with a portion broken away to show the internal construction; and Fig. 3 is an enlarged vertical section on line 3—3, Fig. 1, looking in the direction of the arrow.

The stationary base 1 of the machine, 60 which comprises a hollow or open casting, is provided on each side with an upwardly extending arm or support 2 for the bearing 4 within which is clamped the bearing sleeve 5 for the rotating shaft 6 which extends 65 across the machine from one sleeve to the other. Pivoted upon the inner portion of the sleeve 5 is the tilting head 7, the lower rear portion of which, as at 8, is adapted to swing within the rear portion of the base 70 when the front of the head is tipped up. When the head is in its normal position, as shown in the drawing, its lower front end, as at 9, rests upon a cushioning support 10 of rubber or other suitable material in the 75 front end of the stationary base 1.

In order to prevent the accidental dropping of the head from a raised or tipped position or its too rapid lowering with possibility of injury to the operator or damage 80 to the machine itself, the latter has been provided with a friction braking mechanism arranged to permit free lifting or upward tilting of the head, but to apply a braking resistance to its lowering or downward movement. This mechanism comprises the friction or brake band 11, one end 85

of which is pivotally secured to the upright 2 of the stationary base by means of the screw 12, while the other end is adjustably 90 connected with the first end by means of the screw 13, by the tightening or loosening of which the diameter of the band may be diminished or increased. Supported within the band 11 is the friction or braking ring 95 14, the outer periphery of which is grooved to receive the round band 11. The friction ring 14 is arranged to be disconnected from the tilting head 7 when the latter is being raised, but to be connected thereto by means of a one-direction clutch as soon as the head begins to be lowered. This comprises the clutch ring 15 fixedly secured to the tilting head 7 by means of the screws 16, and having on its periphery the ball-receiving recesses 17 with inclines 18. Within each recess is a ball 19 normally pressed outward up the incline 18 by means of the spring 20

to engage the slightly grooved inner periphery of the friction ring 14. The inclines 18 are so directed and the springs 20 are so located that when the clutch ring 15 is turned in a left-hand or anti-clockwise direction, as seen in Fig. 2, which corresponds to a raising or lifting of the tilting head, the friction ring 14 will remain stationary and disconnected from the clutch ring 15 and tilting head 7. As soon, however, as the tilting head is started to be lowered, which causes the clutch ring to turn in a right-hand or clockwise direction, the friction ring 14 is clutched or connected to the tilting head by means of the balls 19 and clutch ring 15, and the friction band 11, through its frictional engagement with the ring 14, prevents or retards the lowering movement of the tilting head. By turning the adjusting screw 13 in one direction or the other the friction between band 11 and ring 14 can be increased or diminished as desired, and may be made sufficient to overcome the action of gravity altogether, so that the head will remain in any position or inclination, in which case the operator will have to force or press the head down to its normal position. If the operator prefers, however, a less amount of friction may be employed which will be sufficient to prevent accidental dropping of the head when in its fully raised or tilted position, and which will relieve the operator of the greater portion of the weight of the head when it is being lowered to normal position. It will be noted that whatever the adjustment of the friction band, the present device does not interfere with the free raising of the head, but operates only to restrain or retard the lowering movement of the head.

While the present invention has been

illustrated and described as embodied in a buttonhole sewing machine, it is to be understood that its application is not limited to such machine nor its form and arrangement to the specific devices shown, but that it may be employed in many other kinds and types of machines and the form and arrangement of its parts varied. 45

Having thus described the nature and object of the invention, what is claimed is:

1. The combination of a stationary base, a head pivotally mounted upon the base upon a substantially horizontal axis located in the rear of the center of gravity of the head and adapted to have a limited tipping movement about said axis, the front of the head normally resting upon the stationary base and being adapted to be raised by the operator against the action of gravity, and 50 coöperating friction members connected with the stationary base and the tipping head respectively when the head is being lowered, one of said members being automatically disconnected when the head is being raised. 55

2. The combination of a stationary base provided with a pair of upwardly extending bearing supports, a tipping head pivotally mounted upon said supports and adapted 70 to have a limited tipping movement about an axis located behind the center of gravity of the head, the front of the head normally resting upon the base, a friction band secured to one of said supports, means for 75 adjusting the band, a friction ring coöperating with the band, and a one direction clutch for connecting the head and ring when the head is being lowered, said clutch being inoperative when the head is being 80 raised. 75

GEORGE S. HILL.
